[57] CLAIM

The ornamental design for a molded curb stone, as shown and described.

DESCRIPTION

FIG. 1 is a perspective view of a molded curb stone showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is an end elevational view, the opposite end being a mirror image thereof;

FIG. 7 is a perspective view of a second embodiment of a molded curb stone showing my new design;

FIG. 8 is a front elevational view thereof;

FIG. 9 is a top plan view thereof;

FIG. 10 is a rear elevational view thereof;

FIG. 11 is a bottom plan view thereof;

FIG. 12 is a perspective view of a third embodiment of a molded curb stone showing my new design;

FIG. 13 is a top plan view thereof;

FIG. 14 is a front elevational view thereof;

FIG. 15 is a rear elevational view thereof;

FIG. 16 is a bottom plan view thereof; and

FIG. 17 is an end elevational view, the opposite end being a mirror image thereof.
